UNITED STATES PATENT OFFICE

MATHIAS SENZER, OF HIGHLAND PARK, NEW JERSEY

ART OF COAT MAKING

Application filed August 5, 1932. Serial No. 627,654.

My invention relates to the art of making coats for ladies and gentlemen including overcoats and raincoats.

Primarily the invention has for its object 5 to make a coat of neat and stylish appearance by the use of a minimum amount of cloth with minimum waste of material.

Further, it is an object to provide a coat having a full back, front, and top sleeves integral with each other, the front and back parts being sewn together with a side seam extending from armpit to belt line only and the upper and lower front parts being sewn together along the belt line, there being no 15 cross or vertical seam in the back section of the coat.

Further it is an object of the invention to provide a method of getting all of the pattern parts of the coat out of a single rectangular piece of cloth of an area of approximately 20 ten percent less than that now required in cutting the coat according to the conventional methods.

Again it is an object to provide a pattern 25 or method of cutting coats whereby from a given rectangular piece of goods the front, the back, the skirt, top sleeves, under sleeves, facings, top collar, cuffs, belt and pockets may be cut with a minimum waste of cloth 30 and whereby the garment may be finished with less labor than by the use of the patterns and methods of cutting now employed.

Other objects will in part be obvious and in part be pointed out hereinafter.

To the attainment of the aforesaid objects and ends, the invention still further resides in the novel features of construction, combination and arrangement of parts, all of which will be first fully described in the following 40 detailed description, then be particularly pointed out in the appended claims, reference being had to the accompanying drawing, in which:—

Figure 1 is a plan of a rectangular piece 45 of goods folded over on its mid-line and from which my coat is to be cut, the pattern forms being in place and the dotted lines showing the outline of the piece of cloth before it is folded over.

Figure 2 is a front elevation of a coat em-

bodying my invention, a portion of the belt being left untacked to show the waist seam.

Figure 3 is a rear elevation of the coat.

In the drawing in which like numerals and letters of reference designate like parts in 55 all of the figures, 1 is the back of the coat which is in one piece from the neck down to the bottom of the skirt while 2 indicates the upper front quarter sections or breast sections of the coat, they being integral with the 60 back 1 along the shoulder line *j*.

3 is the top sleeve which is also integral with the sections 1 and 2 at the shoulder and lies in its pattern below the breast section 2 and above the lower quarter or front skirt 65 section 6 of the coat.

The under sleeves and the front vertical edge facing strips 5 are cut from the cloth in the upper corner beyond the breast section 2 and above the top sleeve 3.

6 designates the lower front quarter sections of the coat and these are made integral with the back section below the waist line *e*, the same lying to one side of the side line *k* of the back and terminating at the upper edge 75 *e* at the belt line of the garment.

7 is the front edge facing strip for the section 6 which may be left integral with that section and folded over, or it may be cut from the section and sewn to the edge as may 80 be preferred.

The full belt 8 is cut from the cloth below the sections 1, 6, and 7 as shown.

The top collar 9 and the cuffs 10 are cut from the cloth in the space above the back 85 and breast sections of the coat.

The cloth which is located below the top sleeve 3 and above the lower quarter section 6 of the front of the coat is of ample degree to permit one or more pockets 11 to be cut 90 from the same.

a designates the neck opening of the integral back and breast sections, *a'* the corresponding portion of the facing strip 5, the edge *h'* of which is sewn to the edge *h* of the 95 breast section 2. *b*—*i* indicates the arm hole edge of the breast sections 2 while *c* indicates the arm hole edge of the back 1. The edge *b'* of the top sleeve 3 is sewn to the edge *b* of the breast section 2 while the edge 100

c' of the top sleeve is sewn to the edge *c* of the back in making up the coat.

The edges *f* and *f'* of the top and under sleeves respectively are sewn together as are 5 also the edges *g* and *g'*, while the edge *i'* of the under sleeve is sewn to the edge *i* or *c* of the breast section 2 and back 1 respectively.

The edge *d'* of the breast section is sewn to the edge *d* of the back section while the 10 edge *e'* of the breast section 2 is sewn to the edge *e* of the section 6.

The full belt is cut from the bottom edge of the sections 1 and 6 along the line L and after being made up is sewn to the assembled coat so as to cover the belt seam *e*—*e'*. 15

It will thus be seen that I have utilized as much of the cloth as possible in an efficient way, leaving very little waste and enabling me to use a rectangular piece of cloth 20 which experience has shown is approximately ten percent less than that required for cutting a coat by the old methods now in general use.

It should, of course, be understood that 25 the garment may be cut with a curved line at *d*—*d'* instead of a straight line as when it is desired to make the coat a "form-fitting" garment instead of a "box" coat.

From the foregoing description, taken in 30 connection with the accompanying drawing, it is thought that the advantages of my invention will be clear to those skilled in the art.

What I claim is:

35 1. In the art of coat manufacture, the method of cutting coats from rectangular blanks of cloth which consists in laying out the back of the coat, two upper quarter-front sections, two lower quarter-front sections and 40 two top sleeves as an integral structure, the upper quarter sections being integral with the back sections along the shoulders, and the lower quarter sections being integral with the back section along the sides thereof, the 45 top sleeves being integral with the back section and the upper quarter-front sections at the shoulders, cutting the parts to provide arm holes to the edges of which the sleeves are adapted to be sewn, said upper quarter- 50 front sections being cut with edges adapted to be sewn to the back section along vertical lines extending from the arm holes to the belt line of the garment, said upper and lower front sections being cut with cooperating edges 55 adapted to be sewn together along the belt line, under sleeves and front edge facing strips cut from the back at the corners beyond the upper quarter-front sections and above the top sleeves, and locating facing 60 strips along the extreme vertical edge of the lower quarter-front sections.

65 2. In the art of coat manufacture, the method of cutting coats from rectangular blanks of cloth which consists in laying out the back of the coat, two upper quarter-front

sections, two lower quarter-front sections and two top sleeves as an integral structure, the upper quarter sections being integral with the back sections along the shoulders, and the lower quarter sections being integral with the back section along the sides thereof, the top sleeves being integral with the back section and the upper quarter-front sections at the shoulders, cutting the parts to provide arm holes to the edges of which the sleeves are adapted to be sewn, said upper quarter-front sections being cut with edges adapted to be sewn to the back section along vertical lines extending from the arm holes to the belt line of the garment, said upper and lower front sections being cut with cooperating edges adapted to be sewn together along the belt line, under sleeves and front edge facing strips cut from the blank at the corners beyond the upper quarter-front sections and above the top sleeves, and locating facing strips along the extreme vertical edge of the lower quarter-front sections, said method consisting further in cutting a full belt strip transversely along the lower edge of the back and lower front quarter sections. 70 75 80 85 90 95

3. In the art of coat manufacture, the method of cutting coats from rectangular blanks of cloth which consists in laying out the back of the coat, two upper quarter-front sections, two lower quarter-front sections and two top sleeves as an integral structure, the upper quarter sections being integral with the back sections along the shoulders, and the lower quarter sections being integral with the back section along the sides thereof, the top sleeves being integral with the back section and the upper quarter-front sections at the shoulders, cutting the parts to provide arm holes to the edges of which the sleeves are adapted to be sewn, said upper quarter-front sections being cut with edges adapted to be sewn to the back section along vertical lines extending from the arm holes to the belt line of the garment, said upper and lower front sections being cut with cooperating edges adapted to be sewn together along the belt line, under sleeves and front edge facing strips cut from the back at the corners beyond the upper quarter-front sections and above the top sleeves, and locating facing strips along the extreme vertical edge of the lower quarter-front sections, said method consisting further in cutting a full belt strip transversely along the lower edge of the back and lower front quarter sections, and cutting a top collar and cuffs from the blank above the back and between the upper quarter front sections. 100 105 110 115 120 125 130
